UNITED STATES PATENT OFFICE.

JOHN L. DUNNOCK, OF BALTIMORE, MARYLAND.

DESIGN FOR A BOTTLE.

Application filed December 10, 1928. Serial No. 29,204. Term of patent 3½ years.

To all whom it may concern:

Be it known that I, JOHN L. DUNNOCK, a citizen of the United States, residing at Baltimore city, State of Maryland, have invented a new, original, and ornamental Design for a Bottle, of which the following is a specification.

I claim:

The ornamental design for a bottle substantially as shown.

In testimony whereof I affix my signature.

JOHN L. DUNNOCK.
